SETTING TOOL

Application filed April 18, 1932. Serial No. 605,894.

My invention relates to setting tools for use in setting in a well devices such as packers, strainers, liners, and the like.

It is an object of the invention to provide a setting tool which will set a packer or similar device and which can easily be released therefrom when the setting of the packer has been accomplished.

It is a further object to provide a setting tool which is simple and economical in construction and which will not readily get out of order or fail in use.

The invention has been devised for easy assembly, positiveness of operation, and simplicity of construction.

In the drawing a preferred embodiment of the invention has been illustrated. Fig. 1 is a central longitudinal section of the setting tool shown attached to a packer of the canvas type.

Fig. 2 is a side elevation of the packer and packer sleeve, certain parts being broken away for greater clearness.

Figs. 3 to 7, inclusive, are transverse sections taken on the planes 3-3, 4-4, 5-5, 6-6, and 7-7 of Fig. 1.

Figs. 8 and 9 are transverse sections on the planes 8-8 and 9-9 of Fig. 2.

The setting tool is illustrated as employed in setting a packer including a packer barrel 1, a canvas packer 2, and a packer sleeve 3. The packer barrel is threaded at 4 for connection with a strainer or liner below the packer. A flange or ring 5 is fixed to the outer face of the barrel to support the windings of canvas forming the packer 2. At its upper end the canvas is attached by the windings of wire 6 to a nipple 7 forming the lower end of the packer sleeve 3. The packer barrel has a downwardly inclined ratchet thread 8 along its outer surface toward the upper end thereof.

The interior of the barrel at the upper end is formed with grooves or threads 9, which, as shown at 10 in Fig. 2, are interrupted by longitudinal keys or lands 10, at a plurality of points.

The setting tool includes an upper coupling member 11, threaded at 12 to engage with a setting stem which is commonly an

ordinary drill stem. At its lower end the coupling is connected with a nipple 14, the lower end of which has a threaded connection with a bushing 17. The interior of the nipple 14 as its upper end has threaded connection 55 with a guide nut 15, having a central guide opening to receive the upper end of the mandrel 16.

The bushing 17 is a heavy fitting having a central squared opening 18 to receive the 60 squared section 19 of the mandrel. This section of the mandrel has a radial stop flange 20 at its upper end and a similar flange 21 secured at its lower end.

Below the flange 21 the mandrel is cylindrical except at its lower end where it is formed with a flared expander head 22 threaded to engage within a plurality of clamping dogs 23 and force them outward into fixed engagement with the threads or 70 grooves 9 in the upper end of the packer barrel. The interior of the mandrel forms a passage for fluid and is threaded at its lower end at 24 to engage with a wash pipe or the like.

The clamping dogs 23 are shown as four in number of the proper size to engage on their outer surfaces within the grooved areas between the keys 10 in the packer barrel. Each of the four dogs has an upwardly extending so post 25 formed within an opening to receive a pivot pin. A holding ring 26, fitting loosely about the mandrel, has sets of downwardly extending lugs 27 which have slotted openings therein to receive said pivot pins. The 85 slots allow lateral movement of the dogs relative to the ring when said dogs are being handled. Each dog is recessed in its outer periphery to receive a circular spring 28, which tends to move said dogs inwardly against the 90 mandrel.

The bushing 17 has guide sleeve 29 secured at its lower end. This sleeve fits slidably within the upper end of the packer sleeve 3 forming a telescoping connection to allow a 95 limited movement of the packer sleeve relative to the bushing.

The lower end of the packer sleeve is detachably connected thereto for purposes of assembly. The detachable lower end 30 has 100

an upwardly tapered recess 31 to house a spring ring 32, the inner face of which has ratchet teeth to engage the teeth on the outer surface of the packer barrel. Said ratchet ring is tapered upwardly in cross section to fit said recess.

When the packer is lowered into the well at the upper end of the strainer or liner, it is secured to the setting tool as shown in Fig. 1. 10 It will be noted that when the head 22 on the mandrel is screwed within the expander dogs, said dogs will be moved outwardly into gripping relation to the packer barrel.

The downward thrust of the setting stem 15 will force the mandrel 16 downwardly through engagement of the bushing 17 upon the flange 21 and the packer will thus be moved to position.

When the packer is to be expanded, the 20 setting stem will be rotated to screw the mandrel downwardly and release the head 22 from within the clamping dogs. Said dogs will not rotate because of the keys 10 between them. The mandrel will then drop downwardly until the upper flange 20 rides upon the bushing 17. This will allow the clamping dogs to collapse under the action of the spring 28 and the setting stem may then be lowered upon the packer sleeve 3 and move it downwardly to expand the packer. As the packer sleeve moves downwardly upon the barrel 25 the spring ratchet ring 32 will be moved downwardly also, but, through its engagement with the packer barrel, it will not allow 30 the packer sleeve or packer to move back upwardly.

When the packer is set the setting tool will be free of the packer assembly and may easily be withdrawn from the well.

40 The tool has the advantage of easy operation and simplicity in structure and is not subject to failure in use.

What I claim as new is:

1. A setting tool adapted for engagement 45 with a packer barrel, including a setting stem, a tubular mandrel slidable non-rotatably therein, an expander head on said mandrel and clamping jaws mounted on said head and adapted to be expanded by said head to engage said packer barrel.

2. A setting tool adapted for engagement 50 with a packer barrel, including a setting stem, a tubular mandrel slidable non-rotatably therein, an expander head on said mandrel, and clamping jaws mounted on said head and adapted to be expanded by said head to engage said packer barrel, said head being releasable from said dogs to collapse 55 said dogs by a downward screwing of said mandrel.

3. The combination of a packer barrel, a 60 packer thereon, a packer sleeve slidable in a downward direction on said barrel, a setting stem, a mandrel thereon having a limited 65 longitudinal sliding movement in said stem,

a downwardly flared head on said mandrel, having its outer surface threaded, and a plurality of clamping dogs threaded to engage 70 said head and having their outer faces grooved to engage the upper end of said 75 packer barrel, said dogs being releasable by a downward screwing of said mandrel.

4. The combination of a packer barrel, a 80 packer thereon, a packer sleeve slidable in a downward direction on said barrel, a setting 85 stem, a mandrel thereon having a limited longitudinal sliding movement in said stem, a downwardly flared head on said mandrel, having its outer surface threaded, and a plurality of clamping dogs threaded to engage 90 said head and having their outer faces grooved to engage the upper end of said 95 packer barrel, means acting to hold said dogs resiliently on said mandrel, said dogs being 100 releasable by a downward screwing of said mandrel.

5. The combination of a packer barrel, a 105 packer thereon, a packer sleeve slidable in a downward direction on said barrel, a bushing 110 on said stem having a polygonal opening to nonrotatably receive a mandrel, a setting 115 stem, a mandrel thereon having a limited longitudinal sliding movement in said stem, a downwardly flared head on said mandrel, having its outer surface threaded, and a plurality of clamping dogs threaded to engage 120 said head and having their outer faces grooved to engage the upper end of said 125 packer barrel, said dogs being releasable by 130 a downward screwing of said mandrel.

6. A tubular barrel, internal grooves there- 135 in at its upper end, a setting stem, a tubular mandrel slidable nonrotatably in said stem, means to limit the movement of said man- 140 drel in said stem, a head on said mandrel, and clamping means on said head engaging 145 within the grooves in said barrel, said head being releasable from said clamping means to 150 disengage the same from said grooves, and allow said setting stem to move downwardly 155 on said barrel.

7. A tubular barrel, internal grooves there- 160 in at its upper end, a setting stem, a tubular mandrel slidable nonrotatably in said stem, means to limit the movement of said mandrel 165 in said stem, a head on said mandrel and clamping means on said head engaging with 170 in the grooves in said barrel, including a plu- 175 rality of dogs having a threaded engagement 180 with said head and releasable therefrom by a downward screwing of said mandrel, means 185 to hold said dogs resiliently inwardly.

In testimony whereof I hereunto affix my 190 signature this 13 day of April, A. D. 1932.

MARINUS CHRISTENSEN.
